Inventor
JOHN LINDSAY

Attorney.

UNITED STATES PATENT OFFICE

JOHN LINDSAY, OF SAN FRANCISCO, CALIFORNIA

CASEMENT-WINDOW OPERATOR

Application filed August 24, 1925. Serial No. 52,247.

This invention relates to improvements in casement windows, and has particular reference to mechanism for operating the sash or sashes, as the case may be, to open and close.

The general object of the invention is the provision of a construction adapted to provide a hanger or support for the sash or sashes of a casement window and which is adapted to extend into a room and beyond the casement window to which it is applied, so that the sashes of the window may be readily operated to open and to close from a point within the room, and thereby permit of the installation of a fly screen in the window frame and between the sashes and the interior of the room without hindrance to the operation of opening and closing the sashes.

The above and other objects are accomplished by instrumentalities pointed out in the following specification.

The invention is clearly defined in the claims.

A satisfactory embodiment of the invention is illustrated in the accompanying drawings forming part of the specification and in which

Figure 1 is an elevation of a casement window from the interior of a room, and showing my invention applied thereto, parts of the frame being broken away to disclose the construction and relation of other parts.

Figure 2 is a transverse section approximately on the line 2—2 of Figure 1, and looking in the direction of the arrows.

Figure 3 is a fragmentary cross-sectional plan taken on the plane of Figure 2, but showing the sashes in closed position.

Figure 4 is a vertical cross-section taken through the upper portion of the window frame and showing in transverse cross-section a connection between the upper portion of one of the sashes and the head of the frame.

Figure 5 is a view on a slightly reduced scale taken on the line 5—5 of Figure 4, and looking in the direction of the arrows.

Figure 6 is a vertical cross-section taken through the middle lower portion of the window frame.

Figure 7 is a longitudinal section on the

line 7—7 of Figure 6, looking in the direction of the arrows.

Figure 8 is a sectional plan of a modified form of casement window provided with a single shaft and showing the lower part of a modified form of my invention applied thereto.

Figure 9 is a side elevation of the lock casing with a side plate removed to show the lock.

Figure 10 is a detail contracted perspective of one of the shoes and racks, and

Figure 11 is a fragmentary plan view of one of the shoes and racks.

In carrying out my invention, I provide an operating member in the form of a crank handle 5 and dispose this member on the interior side of the window frame *a* so that it may be operated from the interior of the room. As shown in Figure 1, the crank handle 5 is disposed at the middle portion of the lower side of the window frame *a* and is connected to a shaft 6 which extends transversely through the middle portion of a pocket 7 underneath

the stool 8. A bearing in the form of a casing 9 is provided for the inner end of the shaft 6 as shown in Figure 6, and an additional bearing is provided for the outer end of the shaft by means of a casing 10 herein shown as being substantially in the form of an inverted U except that one side is a trifle longer than the other and terminates in a laterally bent portion 11 which is suitably secured by nails or their equivalents 12 to the bottom of the pocket 7. On the outer end portion of the shaft 6 and within the casing 10 I provide a toothed pinion 13 which operates an upper rack member 14 extending through the upper portion of the casing 10 and a lower rack member 15 extending through the lower portion of the said casing 10. The said rack members 14 and 15 extend longitudinally of the sill 16 and are adapted to move in opposite directions when the pinion 13 is turned through the crank handle 5 and shaft 6.

The offset portions 17 of a pair of shoes 18 and 19 are disposed in alignment with the casing 10 and as shown in Figure 6 the upper rack member 14 is connected, as at 20, to the upper face of offset portion 17 of the shoe 19, and

the lower rack member 15 is connected, as at 21, to the lower face of the offset portion 17 of shoe 18. The portions of the shoes 18 and 19 located beyond the casing 10 are provided on their under sides with open-ended recesses 22 which slidably receive the upstanding portion 23 of a track 24 which extends longitudinally of the sill and is secured thereto, as indicated at 25 in Figure 2.

- 10 The sash members 26 and 27 are supported by the shoes 18 and 19 and are moved thereby and connected thereto in any suitable manner. In the present instance I have shown the meeting stiles of the sash members 15 26 and 27 as being provided with sockets in their lower ends which receive pivot pins 28 extending vertically upward from the shoes 18 and 19. The points of connection between the sash members 26 and 27 and the shoes 20 are such that the rabbeted meeting stiles of the sash members are permitted to overlap, when the sash members are in closed position, as shown in Figure 3. In connecting the upper portion of the sash members 26 and 27 25 to the head of a window frame *a*, I arrange a track member longitudinally of a lining 28' which is disposed parallel with the head member 29. The track is preferably of an angular cross-sectional contour with one side portion 30 disposed horizontally and secured as by screws 31 to a longitudinal rabbet in the liner 28'. The other side portion 32 of the track depends vertically downward and is channeled longitudinally as shown in Figure 35 4, the channel of the track opening outwardly through one side and extending into the channel are inverted U-shaped extensions 33 of shoes 34, one of which is shown in Figure 4, the said shoes being connected to pivot pins 40 35 secured in the upper ends of the meeting stiles of the sashes 26 and 27 in alinement with the pivot pins 28 of the lower shoes. The channeled portion of the rail and the inverted U-shaped shoes 33 are respectively disposed in alinement with the lower track and the slots 22 of the lower shoes.

45 A pair of lower links 36 and 37 have their inner ends pivotally connected to fixed points 38 and 39 herein shown in the form 50 of pins extending upwardly from plates 40 fixedly secured to fixed supports 41 within the pocket 7. The outer ends of the links are pivoted to the lower rails of the sash members 26 and 27 at points between the shoes 55 and the free ends of the said sash members. When the sash members are in closed position, as shown in Figure 3, the links 36 and 37 converge toward the meeting stiles of the sashes and when in this position they are in 60 vertical alinement with the upper link members 42 and 43 which are connected to fixed points in the form of screws 44 secured to the lower face of the liner 28' and to the pivot pins 35. With this construction it is obvious 65 that when hand power is applied to the crank

70 handle 5 in Figure 3, the outer ends of the links 36, 37, 42 and 43, or those ends connected to the sashes, will be forced outwardly, whereupon the remote stiles of the sashes, or those in contact with the opposite sides of the window frame *a*, will move outward and away from the window frame and, at the same time, the upper and lower shoes sliding upon their respective tracks and carrying with them the sashes 26 and 27 will move the meeting 75 stiles toward the opposite sides of the window frame. In this movement of the sashes, the links 36 and 37 operate to turn the sashes upon their pivotal connections with their respective shoes, and the turning movement 80 continues until the shoes abut suitable stops arranged in their path of movement.

85 For purposes of illustration, I have shown the stops which are indicated by 45 arranged so as to intercept the shoes after the sashes have turned for approximately 90°. It will be noted that in opening the window the stiles adjacent to the window frame, as distinguished from the meeting stiles, move outwardly and the meeting stiles move away 90 from one another, the sash stiles and window frame being beveled, as indicated by 46, in order to permit of free outward movement of the free sides of the sashes.

95 It is to be further noted that these peculiar swinging movements of the sashes 26 and 27 afford a greater area of ventilating space when the sashes are partly opened, or at an obtuse angle, than would be had if the sashes were pivotally connected to the sides of the window frame.

100 In Figure 2, I show the sashes 26 and 27 as extending in full open position. In this position, the sashes extend almost at right angles to the plane of the window opening. When the sashes are partially opened, they will be inclined at a more acute angle with respect to the plane of the window opening. If now air is blowing parallel with the wall of the building and toward the right when looking at Figure 2, the sash 27 will deflect a portion of the air into the room. This air will circulate through the room and then will flow out through the opening provided between the side of the window casement and the sash 26. The reason for this movement lies in the fact that the air pressure between the sash 27 and the side of the window frame is greater than the air pressure between the sash 26 and the opposite side of the window frame.

115 The reverse is true should the air be moving parallel with the wall of the building and in an opposite direction to that which it formerly took. In this case, the air would be deflected into the room by means of the sash 26, and after circulating through the room, it would flow out through the space provided by the sash 27 and the side of the window frame.

If the air should be coming directly toward the side of the building, that is in a direction at right angles to the plane of the building wall, it would flow through the space provided between the sashes 26 and 27, and after circulating through the room, it would exit through the spaces provided by the sashes 26 and 27 and their respective sides of the frame. It will further be seen that regardless of the direction in which the air is flowing, it will be forced into the room and then out again.

In Figure 8 I show a modified form of my invention in use in connection with a casement window provided with a single sash 47. In this connection, a crank handle 48 is disposed as described in connection with the preferred form of the device and is connected to a shaft 49 which operates a pinion, not shown, but similar in construction to the pinion 13, which is disposed within the casing 50, similar to the casing 10. A single rack 51 is disposed so as to mesh with the teeth of the pinion within the casing 50 and at one end is connected, as at 52, to the offset portion 53 of a shoe 54 that is connected by a pivot pin 55 to the lower end of one of the stiles of the sash 47. The shoe 54 is adapted to slide upon a track similar in construction to the track 23 and in vertical alignment with the track at the upper portion of the window frame 56, and not shown, but corresponding in construction with the track indicated by 30 and 32 in Figure 4. The upper rail of the sash is provided with a shoe similar in construction to the shoe 33 in Figure 4 and designed to slide upon the said upper track and the upper rail is pivotally connected to the sash in vertical alignment with the lower pivotal connection 55 in the same manner as illustrated for the preferred form in Figure 4.

In connection with the modified form, the lower link 57 is greater in length than the corresponding link of the preferred form and extends obliquely between the sash and one side of the frame as shown in Figure 8. A link corresponding in length to the link 57 is provided for the upper portion of the sash.

The operation of the modified form is obvious when taken in connection with the description of the preferred form. The full line position in Figure 8 shows the sash 47 in closed position and the dotted line position shows the sash when opened, the opening being effected by turning the crank handle in a contra-clockwise direction. In connection with the preferred and modified forms, a suitable lock is provided for locking the window against outward movement when closed or in any of its adjusted positions. The preferred form of lock is shown in Figures 6 and 9 where 58 indicates a ratchet wheel rigidly secured to the shaft 6 and disposed within the casing 9. A pawl

59 is pivoted within the casing, as indicated by 60 in Figure 9, and at one end is provided with a push button 61 which projects upwardly through an opening in the upper side of the casing 9. A leaf spring 62 secured as at 63 to the inner side of a wall of the casing 9 is adapted to yieldingly hold the engaging end of the pawl in contact with the teeth of the ratchet 58.

With this construction the pawl yields when the handle 5 is turned to close the sashes from their open position, and when it is desired to open the sash or sashes from the closed position, the button 61 is depressed to disengage the pawl from the ratchet.

Although I have shown and described one embodiment of my invention, it is to be understood that the same is susceptible of various changes; and I reserve the right to employ such as may come within the scope of the appended claims.

I claim:

1. In a window, the combination of slideable and turnable sash mounting means for moving two sashes and interiorly disposed manually operable means connected directly to the window frame and to the sash mounting means for operating the latter and the sashes carried thereby to slide and turn simultaneously.

2. In a casement window construction, guiding means disposed at the bottom of the window, sash moving members slidably disposed in said guide, sashes carried by said sash moving members and extending over said guiding means when said sashes are in closed position.

3. A device of the type described comprising a casement, a sash, means for pivotally and slidably connecting one edge of said sash to said casement, said means including a pair of shoes, having pins rotatably mounted in said sash, links connecting said sash with said casement, said link connecting means including a bracket pivotally secured to each link and screws for connecting each bracket with said casement and manual means for moving one of said shoes.

4. A casement window comprising a window frame, two sashes movable therein, concealed means for simultaneously sliding and swinging said sashes into open or closed positions, exposed manually-controlled means disposed on the inside of said window for actuating said concealed means, and a lock for said sash moving means for preventing the sashes from being manually grasped and swung into a more open position, but permitting the closing of the sashes.

5. A casement window comprising a window frame having beveled sides, sashes movable in said frame and having beveled edges abutting the beveled sides when the sashes are closed, the adjacent edges of said sides being designed to abut one another, and to

have overlapping portions making a water tight closure, and concealed means including an exposed operating handle for simultaneously sliding and swinging said sashes into open position, the initial movement causing the beveled sash edges to swing away from the beveled frame edges and the abutting sash edges to move away from each other.

JOHN LINDSAY.
